Primary Examiner—Adir Aronovich(74) *Attorney, Agent, or Firm*—Brinks Hofer Gilson & Lione(57) **CLAIM**

I claim the ornamental design for a LCD video projector, as shown and described.

DESCRIPTION

FIG. 1 is a front and right side perspective view of a LCD video projector of the present invention;

FIG. 2 is a front elevation view thereof;

FIG. 3 is a top plan view thereof;

FIG. 4 is a right side elevational view thereof;

FIG. 5 is a left side elevational view thereof;

FIG. 6 is a bottom plan view thereof; and,

FIG. 7 is a rear elevation view thereof.

The broken line showing of LCD video projector is included for the purpose of illustrating environment and forms no part of the claimed design.
